UNITED STATES PATENT OFFICE.

SAMUEL BOWMAN, OF LANCASTER, PENNSYLVANIA.

DESIGN FOR A BREAD AND CAKE KNIFE.

49,295.

Specification for Design.

Patented July 4, 1916.

Application filed April 17, 1916. Serial No. 91,804. Term of patent 14 years.

To all whom it may concern:

Be it known that I, SAMUEL BOWMAN, a citizen of the United States, residing at Lancaster, in the county of Lancaster and State of Pennsylvania, have invented a new, original, and ornamental Design for Bread and Cake Knives, of which the following is a specification, reference being had to the accompanying drawing, forming a part thereof.

The figure is a side elevation of a bread and cake knife, showing my new design.

I claim:

The ornamental design for a bread and cake knife, as shown.

SAMUEL BOWMAN.

Witnesses:

JOHN F. HEINITSH,
W. J. LEIBBY.
